[57] CLAIM

The ornamental design for a display rack for spice container or the like, shown and described.

DESCRIPTION

FIG. 1 is a perspective view of a display rack for spice containers or the like showing our new design;

FIG. 2 is a left side elevational view as seen when in use; the right side being a mirror image thereof;

FIG. 3 is a top plan view thereof.

The rear and bottom views are flat and unornamented.
